FLOORING JACK

Leo H. Lab, Flint, Mich.

Application February 6, 1950, Serial No. 142,669

1 Claim. (Cl. 254—16)

1

This invention relates in general to an improved flooring jack, and more particularly to a type thereof for positioning and holding a floor board against an adjacent board and upon means, such as rafters or a subfloor, to which said floor board is to be secured.

Persons, such as carpenters, have long recognized the need for an easily operable, inexpensive, positive acting device, herein referred to as a flooring jack, for positioning and holding a floor board against an adjacent board and upon a supporting means, such as rafters or a subfloor, while being secured thereto, as by nailing. Such a flooring jack is particularly desirable in laying floor boards of the tongue and groove type. Previous attempts to produce such a flooring jack have either failed or have resulted in a device receiving very limited acceptance at best.

Accordingly, a primary object of this invention is the provision of an improved flooring jack for positively engaging, positioning and holding a floor board against an adjacent board and upon supporting means, such as rafters or a subfloor, upon which said floor board is to be secured.

A further object of this invention is the provision of a flooring jack, as aforesaid, which can be easily operated by unskilled workmen and which affords a high mechanical advantage.

A further object of this invention is the provision of a flooring jack, as aforesaid, which can be quickly assembled or disassembled for easy transport.

A further object of this invention is the provision of a flooring jack, as aforesaid, which is safe to operate and adequate in structure under severe conditions of operation.

Other objects and purposes of this invention will become apparent to persons familiar with this type of equipment upon referring to the accompanying drawings and upon reading the following specification.

In meeting those objects and purposes heretofore mentioned, as well as others incidental thereto and associated therewith, I have provided a flooring jack comprising a body member having a cylindrical passage therein opening through one end thereof, and a crossbar secured to the opposite end. One end of a thrust bar is slidably disposed within the passage in said body member and extends therefrom, the extended end being provided with a weight and a plurality of pointed pins extending substantially radially from said bar. A lever handle is pivotally supported near one end thereof upon said body member so that said near end is engageable with said bar, and further so that said handle extends in the opposite direction to the extent of said pins.

2

Thus, when said flooring jack is assembled, a movement of said lever handle will effect a corresponding movement of said thrust bar within said passage. The lever handle is pivoted upon the body member by means permitting complete disengagement of the thrust bar and the lever handle from the body member.

For illustrations of a preferred embodiment of my invention, attention is directed to the accompanying drawing in which:

Figure 1 is a side elevation view of the flooring jack to which this invention relates.

Figure 2 is a sectional view taken along the line II—II of Figure 1.

Figure 3 is a sectional view substantially as taken along the line III—III of Figure 2.

Figure 4 is a sectional view substantially as taken along the line IV—IV of Figure 3.

As shown in Figures 1 and 2, the flooring jack 20 is comprised of a T-shaped body member 11, a thrust bar 12 and a lever handle 13. The body member 11 has a stem 14, which is substantially cylindrical in this embodiment of the invention, and a flange, or crossbar 15, which is preferably integral intermediate the ends thereof with one end of the stem 14, and perpendicularly disposed with respect thereto. The crossbar 15 is provided with a groove 16 extending along the side thereof remote from the stem 14. Said groove is preferably slightly deeper and slightly wider than the average length and thickness of the tongue 17 on a standard tongued and grooved floor board 18.

A strike boss 21 (Figure 2) may be provided on the cross bar 15 on the opposite side thereof from the groove 16 for purposes hereinafter discussed in detail. The strike boss 21 preferably, but not necessarily, extends in the same direction as the stem 14, and is disposed intermediate said stem and one end of said crossbar 15.

The stem 14 is provided with a pair of spaced, substantially parallel and co-extensive, lever bosses 22 and 23 (Figures 2 and 4) which are integral with said stem 14 and extend in a direction substantially perpendicular to a plane defined by the stem 14 and the crossbar 15. Said lever bosses are provided with a pair of co-axial pivot openings 24 and 25 near the extended ends thereof.

The stem 14 is provided with a cylindrical passage 26 (Figures 3 and 4), preferably co-axial with said stem 14, extending from a point therewithin near the crossbar 15 and opening out through the opposite end of the stem. An elongated lever slot 27, parallel with and radially penetrating the wall of the stem 14 and communicating with the passage 26 therein, is pro-

vided in said stem between the lever bosses 22 and 23.

The thrust bar 12 (Figures 1 and 3) is comprised of an elongated cylindrical portion 28, which is snugly but slideably receivable within the cylindrical passage 26 in the stem 14, and is slightly longer than said passage 26. A weight portion 29, which is preferably integral with said cylindrical portion 28, is disposed at that end thereof which extends out of the passage 26. A plurality, here three, of gripping pins 31 are secured to the weight portion 29 so that they extend therefrom in substantially the same direction, which direction is preferably, but not necessarily, at an angle of approximately 70 degrees to the longitudinal axis of the cylindrical portion 28, and preferably inclined away therefrom.

The cylindrical portion 28 of the thrust bar 12 is provided with a diametrically disposed lever opening 32 (Figures 3 and 4), which is preferably perpendicularly disposed to an imaginary line through the points of the gripping pins 31. The lever opening 32 is positioned in the cylindrical portion 28 for alignment with substantially any portion of the lever slot 27, when said portion 28 is disposed within the passage 26.

If the body member 11 and thrust bar 12 are cast from a relatively light and soft material, such as aluminum or magnesium, the lever opening 32 in the thrust bar 12 is preferably provided with a steel insert 33 at the end thereof adjacent to the weight 29.

The lever handle 13 (Figures 1, 3 and 4) is comprised of a relatively long, handle portion 34, and a relatively short, lever portion 35 integral and co-axial with said handle portion 34. The lever portion 35 is designed for insertion through the lever slot 27 and into the lever opening 32 in the thrust bar 12, said lever portion being snugly engaged by the end walls of the lever opening 32. The lever handle 13 is provided with a pivot opening 36 at the junction of the handle and lever portions thereof, which is alignable with the pivot openings 24 and 25 in the lever bosses 22 and 23, respectively, when the lever portion 35 is disposed within the lever opening 32 in the thrust bar 12. A pivot pin 31, which is inserted through the pivot openings 24, 25 and 36, is sufficiently long to be engaged by means, such as a cotter pin 38, for retaining said pivot pin 31 in place.

When thus assembled, the lever handle 13 is pivotable through an arc in excess of 90 degrees, including 45 degrees to either side of a vertical position.

When the flooring jack 10 is assembled, as above described, it is ready for operation. In using said flooring jack, the crossbar 15 is preferably first placed against the edge of a floor board 18 (Figure 1). The upper end of the lever handle 13 is then moved in a direction away from said floor board 18, thereby causing the weight 29 on the thrust bar 12 to be drawn toward the stem 14. If the flooring jack 10 is being used with floor boards 18 of the tongue and groove type, engagement between the tongue 17 and the groove 16 in the crossbar 15 may be insured by tapping the extended end of the strike boss 21 with means, such as a hammer. The gripping pins 31 are imbedded in the means, such as the sub-floor 39 supporting the floor board 18, by pressing on the top of the weight 29 at the extended end of the thrust bar 12. The upper end of the lever handle 13 is then moved in a direction toward the floor board 18, thereby

effecting a tendency for the extension of the thrust bar 12 out of the cylindrical passage 26 in the stem 14. However, since the gripping pins 31 are imbedded in the sub-floor 39, movement of the thrust bar is substantially prevented. Thus, said movement of the lever handle 13 toward the floor board 18 causes the crossbar 15 to bear tightly against the floor board 18, thereby pressing said floor board firmly against the board, or other means, adjacent to that side of the floor board 18 remote from the crossbar 15.

After the floor board 18 has been permanently placed in position, as by nailing, the flooring jack may be disengaged from said floor board 18, for use with the next floor board to be laid, by simply moving the upper end of the lever handle 13 toward the weight 29, or away from the floor board 18. The operation above described may then be repeated with said next floor board.

After the use of the flooring jack 10 has been completed, it may be disassembled for easy transportation by removing the pivot pin 31, thereby permitting the disengagement of the lever handle 13 and the thrust bar 12 from the body member.

Although the above mentioned drawings and description apply to one particular, preferred embodiment of the invention, it is not my intention, implied or otherwise, to eliminate other variations or modifications which do not depart from the scope of the invention unless specifically stated to the contrary in the hereinafter appended claim.

I claim:

In a device for positioning a floor board against an adjacent board and upon a supporting means, the combination comprising: a cylindrical body member having a coaxial passage therein opening through one end thereof, said member having an axially aligned slot extending therewith and communicating with said passage intermediate its ends; a pair of parallel, coextensive bosses secured to said member along opposite longitudinal edges of said slot; a cross bar secured to the other end of said member and defining therewith a plane perpendicular to said bosses, said cross bar having a groove along that side remote from said member and having a boss on the opposite side thereof spaced from said member; a thrust bar having one end slidably disposed within said passage and having an opening therethrough near said one end and aligned with said slot, the other end of said bar being weighted and having gripping means extending therefrom in a direction substantially perpendicular to said plane and remote from said slot; and a lever having one end extending through said slot and into said opening, and pivotally supported near said one end upon said bosses, whereby movement of said lever toward said cross bar effects movement of said thrust bar with respect to said member.

LEO H. LAB.
